UNITED STATES PATENT OFFICE.

JAMES C. COVERT, OF WEST TROY, NEW YORK.

DESIGN FOR A HARNESS-HOOK.

SPECIFICATION forming part of Design No. 23,802, dated November 13, 1894.

Application filed October 13, 1894. Serial No. 525,842. Term of patent 14 years.

To all whom it may concern:

Be it known that I, JAMES C. COVERT, a citizen of the United States, residing at West Troy, in the county of Albany and State of New York, have invented and produced a new and original Design for Hooks; and I do hereby declare the following to be a full, clear, and exact description of the same, reference being had to the accompanying drawings, forming a part thereof.

This invention relates to a new and original design for hooks and it consists in the peculiar ornamental shape and configurations therein hereinafter described and shown in the accompanying drawings, wherein—

Figure 1 represents my design in front elevation and Fig. 2 represents the same in side elevation.

In the drawings A designates the curved hook end the shank of which is separated and curved outwardly as at B into two parallel branches C C' the space c between the branches being substantially U-shaped. The branches C C' have flat vertical inner and outer side walls a and their upper portions

are curved upwardly and then slightly down as at F. From the rear ends of the outer flat sides of the branches C C' extend the bars E forming the inner side bar of the substantially rectangular loop F'. Extending across 30 the space between the outer ends of the branches C C' is a cylindrical cross bar G while between said cross bar and the hook is the bar H spanning the space between the branches.

35

The essential features of the design are the branches C C' with the space between, and the spanning bars G and H.

Having thus described the invention, what is claimed as new, and desired to be secured 40 by Letters Patent, is—

The design for a hook substantially as shown and described.

In testimony whereof I affix my signature in presence of two witnesses.

JAMES C. COVERT.
